MACHINE FOR MANUFACTURING EDIBLE
ICEWilly Dummler, Steinau, Kreis Schluchtern,
GermanyApplication June 28, 1939, Serial No. 281,697
In Germany July 2, 1938

10 Claims. (Cl. 62—114)

This invention relates to a machine for manufacturing edible ices in which the mass of edible ice which is located in a rotating, externally cooled receptacle or freezer is constantly conveyed to the wall of the freezer and then stripped therefrom by means of a stripper which is adapted to move up and down over the wall of the freezer.

According to the present invention the inside wall of the freezer co-operates with a guide vane arranged at a distance from the said wall, and the stripper is provided with two or more stripping knives arranged at a distance from one another corresponding to their height of stroke, and leaving between them a passage through which the edible ice mass may pass. In this arrangement the drive of the stripper is such that the stripper impinges upon the wall of the freezer only during its upward movement. In this manner, the mass removed by the stripping knives from the wall of the freezer is caught by the guide vane and reconveyed to the wall of the freezer by means of the surface of the vane which is arched in the direction of rotation of the wall of the freezer.

As a further development of the inventive idea the guide vane is suspended in the freezer so as to be manually rotatable about its vertical longitudinal center axis, and the edge which is opposite the arched guide surface is, in the case of a modified form, provided with stripping knives. On the spindle of the guide vane there is provided a limiting arm provided with a set screw, said arm cooperating with a stationary abutment, which determines the width of the slot remaining between the wall of the freezer and the guide vane and the working position of the latter. The abutment is adapted to be rotated about a pivot out of the track of the limiting arm, so that when the abutment is thus rotated out of the way the vane may be pivoted about its axis until the stripping knives impinge upon the wall of the freezer. In this position the guide vane constitutes a mold in which the finished edible ice mass collects. The guide vane is provided with a bottom plate the edges of which are also designed in the manner of strippers. The vane with its spindle is detachably mounted in bearings in the machine frame, so that the vane together with the edible ice mass collected in the mold therein may be lifted out of the freezer.

Further details of construction and advantages thereof are hereinafter explained in detail with

reference to the constructional forms illustrated in the drawing, in which

Figures 1 and 2 illustrate a vertical section of the new machine, the plane of one section being displaced through 90 degrees with respect to the other section.

Figures 3 and 4 illustrate the construction of the bearing of the guide vane.

Figures 5 and 6 are horizontal sectional views of the freezer taken on the line V—V in Figure 3, looking in the direction of the arrows, and illustrate the two end positions of the guide vane, Fig. 6 showing the position during the freezing operation.

The machine consists of an edible ice receptacle or freezer 1, which is inserted in a double-walled pail or casing 2, and a supporting bracket 3, which accommodates the motive driving elements. The entire drive is effected by means of the freezer shaft 4 which is driven from a motor 7 by the gearwheels 5, 6. The edible ice freezer 1 is keyed on and rotates with the freezer shaft 4, in a step bearing 8. For removal of the freezer 1, the freezer shaft 4 itself is split into two lengths and adapted to be locked together by means of a sleeve 9. The driving of the stripping arrangement is effected by means of a worm 10 fixedly carried on the freezer shaft and actuating a worm wheel 11 which is coupled to a shaft 12. On the shaft 12 is mounted a crank 13 which by means of a crank pin 14 imparts up-and-down movement to a connecting rod 15. The connecting rod 15 is rotatably attached at a second point to the pin 16 to which is attached an oscillating arm 17, the latter being rotatably mounted on the bracket 3 by means of a pin 18. A stripper arm 19 is adapted to be hung on and removed from the pin 16, the stripper 21 being pivotally carried by said stripper arm 19 by means of a pin 20. The stripper 21 carries two off-set and projecting knives 22. Owing to the upward movement during reciprocation of the connecting rod 15, the stripper arm 19 and the oscillating stripper 21 are raised (Fig. 3). The requisite contact pressure of the stripper 21 upon the wall of the freezer is obtained by means of a spring 23, which acts upon a cam 24 which is carried on the stripper arm 19. The spring 23 rests firmly upon an eyelet of the connecting rod 15. When the crank 13 and with it the connecting rod 15 move downwardly the stripper arm 19 is engaged by means of a stop 26, which is fixedly attached to the connecting rod 15, with the aid of the cam 24, with the result that the stripper 21 is displaced

away from the wall of the freezer. During the upward movement of rod 15 the stop 26 releases the cam 24 so that the force of the spring 23 is free to act and press the stripper knives 22 against the side-walls of the freezer.

For the purpose of gathering and reconveying the stripped mass of edible ice to the wall of the freezer a guide vane 27 is arranged within the freezer 1. The vane 27 is rotatably adjustably suspended in the holder 29 by means of a carrier rod 28, and its rotatable adjustment is limited by engagement of the arm 30 fixedly carried on rod 28, with the abutment 31 which is rotatably adjustable in position. The abutment 31 is rotatable about a pin 32 on the carrier arm 29. For the purpose of regulating the adjustment of the vane 27 and its minimum spacing from the freezer wall, a set screw 33 is provided in the arm 30, said screw being positioned to impinge upon the abutment. When the freezer 1 is to be emptied the abutment 31 is pivoted outwardly about the pin 32 so that the arm 30 and with it the vane 27 may be rotated by means of the rotary lever 34. The rod 28 has one portion thereof reduced in diameter in such manner that after being raised in the slotted bearing 35 (Fig. 4) it can be removed therefrom.

The vane 27 possesses an arched portion 36 and a straight portion 37 extending beyond the spindle 28, the edge of said straight portion being provided over its entire length with strippers 39 held under pressure from the springs 38. The back of the arched portion 36 constitutes in one position of the vane 27 (Fig. 6) a guiding surface, with the aid of which the mass of edible ice is conveyed to the wall of the freezer.

When the edible ice has been completely frozen the vane 27 is manually rotated so that the strippers 39 come into contact with the wall of the freezer. In this manner the mass is removed from the wall of the freezer and is collected in the mold of the guide vane 27, which is provided with a bottom 40, so that the mass can be lifted from the freezer together with the vane 27.

The bottom 41 of the freezer 1 is level so that the guide vane 27 can be rotated thereon without being raised therefrom. The freezer 1 rests upon an internal shoulder provided in a dish-shaped plate 42 in such a manner as to leave a hollow space 43 under the bottom of the freezer, so that only a slight freezing action occurs at the said bottom. The edge of the bottom plate 40 acts as a stripper for the purpose of collecting the mass from the bottom of the freezer.

What I claim and desire to secure by Letters Patent of the United States is:

1. A machine for manufacturing edible ice comprising a rotating, externally cooled freezer, a stripper moving up and down along the inside wall of the freezer, mechanical means for conveying the edible ice mass back to the wall of the freezer, said means consisting of a guide vane which is arranged at a distance from the inside wall of the freezer with which it is adapted to co-operate, the said stripper being provided with a plurality of spaced stripping knives the extreme distance between which is less than the height of said inner wall leaving between them a passage through which the mass of edible ice may pass.

2. A machine according to claim 1, in which the surface of the guide vane which conveys the mass of edible ice to the wall of the freezer is arched in the direction of rotation of the pan,

the opposite edge of said vane being provided with strippers which impinge upon the wall of the freezer.

3. A machine according to claim 1, in which the guide vane extends to the bottom of the freezer and is provided at the lower end thereof with a bottom plate the edges of which operate as stripping means.

4. A machine according to claim 1 in which the spindle of the guide vane is guided in a slotted bearing on the bearing arm, the portion of the said spindle which in the working position of the guide vane is located below the portion which is encased by the bearing being reduced in diameter so that it can be easily removed through the slot after being raised.

5. A machine according to claim 1, a rod unit connected to said stripper and comprising a pair of pivotally connected lever members, a crank connected for driving said rod unit, an oscillating lever, a fixed pivot for pivotally mounting one end of said oscillating lever, the other end of said oscillating lever being pivotally mounted on said rod unit on the pivot connecting said lever members, and means for normally holding said rod unit with its said lever members in the extended position.

6. A machine according to claim 1, a rod unit connected to said stripper and comprising a pair of pivotally connected lever members, a crank connected for driving said rod unit, an oscillating lever, a fixed pivot for pivotally mounting one end of said oscillating lever, the other end of said oscillating lever being pivotally mounted on said rod unit on the pivot connecting said lever members, and resilient means connected between said lever members for normally holding said rod unit with its said lever members in the extended position.

7. A machine according to claim 1, a rod unit connected to said stripper and comprising a pair of pivotally connected lever members, a crank connected for driving said rod unit, an oscillating lever, a fixed pivot for pivotally mounting one end of said oscillating lever, the other end of said oscillating lever being pivotally mounted on said rod unit on the pivot connecting said lever members, the lower lever member which carries the stripper being extended beyond the pivot connecting the other lever member, a cam carried on said lower lever member, and a spring carried on said other lever member and engaging said cam, whereby said stripper contacts said freezer wall on the upstroke but is displaced therefrom on the downstroke.

8. A machine according to claim 1, a spindle mounted vertically centrally of said freezer, a limiting arm carried on said spindle and projecting transversely therefrom, and an abutment mounted for engaging said limiting arm, said guide vane being mounted on said spindle and being positioned in operative position by engagement of said arm with said abutment.

9. A machine according to claim 1, a spindle mounted vertically centrally of said freezer, a limiting arm carried on said spindle and projecting transversely therefrom, an abutment mounted in position to engage said arm, an adjustable set screw carried on said arm and positioned to impinge on said abutment to control the spacing between said arm and said abutment, said guide vane being mounted on said spindle and being spaced from the freezer wall in operative position by engagement of said set screw with said abutment.

10. A machine according to claim 1, a spindle mounted vertically centrally of said freezer, a limiting arm carried on said spindle and projecting transversely therefrom, stationary frame mounting means, and an abutment member pivotally mounted on said frame mounting means and positioned for normally engaging said limit-

ing arm but being pivotally displaceable out of the path of said limiting arm, said guide vane being mounted on said spindle and being positioned in operative position by engagement of 5 said arm with said abutment member.

WILLY DUMMLER.
